TELEPHONE RECEIVER

Philip Norton Roseby, Woodvale, near Southport, England, assignor to Associated Telephone & Telegraph Company, Chicago, Ill., a corporation of Delaware

Application September 25, 1939, Serial No. 296,415
In Great Britain September 26, 1938

3 Claims. (Cl. 179—117)

The present invention is concerned with improvements in or relating to receivers for audio currents commonly referred to as telephone receivers because of their general use in telephony, but of course applicable to receiving electrical currents of any kind capable of giving an audible signal. Such receivers as is well-known, commonly include a permanent magnet system and the effect of the permanent magnet is to create a magnetic field which extends beyond the receiver and may deleteriously effect instruments or the like in its neighbourhood. In order to overcome this disadvantage it has been proposed to provide an iron case completely surrounding the receiver. This has, among others, the disadvantage that it makes the receiver unduly heavy.

An object of the present invention is to overcome this disadvantage in a more efficient manner while at the same time considerably reducing the weight of the receiver.

One of the features of the invention to attain this end is the employment of a small bar magnet of material specially capable of withstanding self-demagnetisation so that it can be employed in short lengths, for instance, that known under the registered trade-mark "Alnico," which is an alloy of aluminium, nickel and cobalt in place of the usual C-shaped, ring-shaped or horse-shoe-shaped permanent magnet of tungsten steel or like material which necessitates a comparatively long length of magnet to ensure the retention of the strength of the magnet.

The second feature of the present invention is the employment of a casing of aluminium or similar light material having insets of iron sheeting so as to completely surround the magnetic system other than at the end at which the diaphragm is located, the diaphragm itself serving to act as a shield as well as to perform its normal function. In order to assist in the reduction of stray magnetic fields an auxiliary magnet is located in the casing in appropriate relationship to the bar magnet so as to act in a similar way to the second magnet in an astatic galvanometer, that is to say, the magnet may be bar-shaped and arranged parallel and at some distance from the main bar magnet end having its poles of opposite polarity, the position being so chosen as to have the minimum effect upon the flux of the permanent magnet which reaches the diaphragm while with a maximum effect upon the stray flux.

The invention will be better understood by referring to the following description in conjunction with the accompanying drawing.

Fig. 1 is a plan view of a receiver according to the invention.

Fig. 2 is a cross section of the receiver.

Figs. 3 and 4 are plan and elevation respectively of a pole piece of the receiver.

The telephone receiver has a casing 1 which may be of moulded insulating material. In addition there is an inset casing 2 which may be of aluminium or other similar light metal. The receiver cap of similar material to the casing is shown in Fig. 2 in two embodiments 3 and 3'. The embodiment 3' is provided with openings 4 for the free egress of moisture. The diaphragm 5 is clamped between the casing and cap in the normal manner. Inside the inset casing 2 there is provided a thin annular ring 6 of soft iron located against the sides of the casing and serving as a magnetic shield for those sides. A further thin soft iron disc 7 is also provided located in the face of the casing 1 between the casing 1 and the inset casing 2. This is also for screening purposes. In the casing 1 openings 8 are provided for the insertion of the ends of the holding clip.

Supported in the base of the casing are two L-shaped pole pieces 9. These consist of a vertical arm 10 and a horizontal arm 11. The latter is drilled for mounting the pole pieces on pillars 12. These pillars extend through the inset casing 2 and the magnetic disc 7 and are secured in the base of the casing 1, a collar on the pillar rests on the inset casing 2. Located between the pole pieces is the bar magnet 13 which may be of magnetic material strongly resistant to self-demagnetisation such as that known under the trade-mark "Alnico." This material has a high coercivity. This magnet is a rectangular block and extends between the pole pieces in close contact therewith. The pole pieces are provided with projections 14 which extend beyond the bar magnet and are drilled to provide support for posts 15 which extend therebetween. The upper post 15 shown in Fig. 1 is tapped for the insertion of a screw carrying a bracket member 16. This latter is a rectangular bracket into which fits a further bar magnet 17 which may be a rectangular block of the same shape as the bar magnet 13. This bar magnet 17 is held rigidly between the bracket over the top of the magnet and the inset casing 2 at the bottom of the magnet. The magnetic ring 6 provides extra support at the sides of the magnet. The post 15 in the lower half of Fig. 1 is tapped for the attachment of a strain cord bracket 18. This is provided for the attachment of the cord which comes through the opening 24 in the casings.

The pillars 12 also serve as supports for terminal brackets 19. These terminals which are mounted so as to be insulated from the pillar 12 are prevented from rotating about the pillar by means of downturned flaps 20 which are inserted in raised insulating pillars 21 forming part of the casing 1. The terminal brackets 19 are connected to the respective coils by means of the wires 22. These coils 23 are the usual exciting coils.

The direction of magnetisation in the permanent magnet 13 and the shielding magnet 17 are so arranged that stray magnetic field from the permanent magnet is taken up by the shielding magnet. In this way a very efficient method of eliminating or reducing to negligible dimensions the stray magnetic field of a receiver has been achieved.

I claim:

1. A telephone receiver comprising a diaphragm, pole pieces adjacent the diaphragm, a permanent magnet clamped between said poles, a second permanent magnet arranged parallel to

but in opposition to the first magnet, and a thin metallic shield surrounding said magnets for retaining the influence thereof within the shield.

2. In a telephone receiver having a diaphragm and the usual permanent magnet structure for operating the diaphragm, a casing of insulation enclosing said structure, a light metallic non-magnetic lining for said casing, a thin shell of magnetic material of tubular shape inside the lining encircling the structure, and a disc of magnetic material in the bottom of the casing covering one end of the tubular shaped shell.

3. A telephone receiver comprising a diaphragm, pole pieces adjacent said diaphragm, a permanent magnet clamped between said pole pieces, a support secured to said pole pieces, and a second permanent magnet secured to said support in a position parallel to but in opposition to said first magnet and adjacent said pole pieces, and a shield for retaining the influence of said magnets therewithin.

PHILIP NORTON ROSEBY.
